BOTTLE-LABELING MACHINE.

1,007,080.

Specification of Letters Patent. Patented Oct. 31, 1911.

Application filed May 3, 1909. Serial No. 493,450.

To all whom it may concern:

Be it known that I, WILLIAM J. EVANS, a citizen of the United States, residing at Akron, in the county of Summit and State 5 of Ohio, have invented certain new and useful Improvements in Bottle-Labeling Machines, of which the following is a specification.

My invention relates to a bottle labeling 10 machine, and the invention consists in a machine adapted to paste labels and apply the same to bottles mechanically and thereby substitute and dispense with hand labor, all substantially as shown and described and 15 particularly pointed out in the claims.

In the accompanying drawings, Figure 1 is a vertical sectional elevation of the machine on the line of the suction mechanism adapted to receive and carry the label to the 20 point of delivery upon the bottle, as hereinafter fully described. Fig. 2 is a sectional elevation of the machine a quarter turn to the right from position in Fig. 1 and showing the position and manner of delivery of 25 the label to or upon the bottle, also as hereinafter more fully described. Fig. 3 is a horizontal sectional plan view of the parts as they appear successively in Figs. 1 and 2, it being understood that Figs. 1 and 2 are 30 upon radial lines a quarter turn apart, while the present view shows full lines of said parts in both operating positions and as they occur successively as to position but simultaneously in point of time. Fig. 4 is 35 a perspective view of the two hubs through which both the suction and the blast for the labels are controlled. Fig. 5 is a side elevation of the machine partly in section and particularly of Fig. 3, the section being on 40 a line substantially between the paste pot and the paste applying roller. Fig. 6 is a perspective view of a guard mechanism for the labels before the suction drum.

As thus shown the machine is designed to 45 perform all the labor involved in supplying, pasting and sticking labels upon bottles, the same being performed in three several successive and progressive steps completing the 50 operation. To this end the machine is provided with suitable pockets, wherein the labels are bunched one behind the other and fed or supplied one at a time to a suitable carrying mechanism comprising suction drums. These drums are adapted to be rotated, first to pasting position for the labels,

which are pasted on their inside and held by suction until they reach the releasing position and relation before the bottle, at which place the suction is displaced by a blast of air which throws or blows the label 60 upon and about the bottle in such manner as to adhere the same thereto. The bottles are in turn fed or carried around step by step to receiving position for the label, and thus the work is carried forward automatically and accurately as will hereinafter more fully appear.

The machine is supported upon a frame or bed B of suitable size and elevation, and a vertically disposed cylinder, C, is seated 70 in or about an opening in said bed and provided with an exhaust opening *a* in its bottom head A. Said head is removably screwed into the lower extremity of said cylinder and has a relatively long sleeve 75 shaped bearing for cam actuated slidable rod E, which extends up into said cylinder and is adapted to be reciprocated axially therein as will clearly appear. The said cylinder C and its head A are stationary and 80 the opposite or upper head *b* of the said cylinder provides a suitable bearing for the tubular shaft F through which air blast is supplied for blowing the labels upon the bottles. In this connection it is to be observed that said tubular blast shaft or pipe 85 F is connected with two reciprocating but otherwise stationary hubs H and H' respectively. That is two are employed in this instance, but the principle of my invention 90 is equally and fully embodied in a single hub, the double use of hubs in this case having the advantage of handling labels for either the body or the neck of a bottle or for both at the same time as may be desired. Otherwise only a single hub might 95 be employed and for either the body or the neck of the bottle. Said hubs are unitary or in one piece in this instance, and connected by a neck *h* which is provided with 100 a bore 2 lengthwise through said neck and open to blast pipe F and to lateral ducts 3 and 4 respectively at its ends. These ducts or ports are the blast passages above referred to for blowing the labels upon the 105 bottles and are in constant open communication with said blast pipe F. Two drums, D and D', are employed in connection with said hubs, so-called. These drums are mounted one upon the other and upon a ro- 110

tatable gear G as a base support therefor and are otherwise sleeved to rotate about cylinder C as a bearing therefor. As to these hubs and drums, it will be observed 5 that they are of different depths respectively and that the upper drum is somewhat larger than the lower one in diameter. The latter difference is more especially to adapt the upper drum to reach the neck of 10 the bottle, and the difference in depth is on account of the difference in widths of labels employed for the body and neck of the bottle respectively. Otherwise they might have the same relative sizes, and both 15 drums are rotated intermittently or have measured or broken rotation around said cylinder, while the said hubs do not rotate but have a vertical reciprocating movement through their operating rod E. Said rod 20 is yoked to the lower hub as clearly seen in Figs. 1 and 2 and is actuated by cam wheel W. Said wheel is splined on a transverse shaft S, Fig. 2, and is provided with a series of so-called cam teeth or projections 25 somewhat resembling saw-teeth and having straight backs 6 running at an inclination to elevations 7 where each cam ends, while the said shaft E has a roller 8 on its bottom adapted to run upon the said straight backs 30 successively and raise the said hubs H and H' through shaft E to such elevation as will open and close their relations successively to the air blast and the air suction, respectively. Said drums furthermore are 35 subdivided by means of partition walls 9 into a series of equal compartments, eight in number in this instance, and which walls extend from the outer wall of the drums radially against the surface of cylinder C 40 where they engage closely enough to form practically air tight bearings and compartments. Said cylinder has openings or holes 10 and 12 respectively which communicate with the ducts 3 and 4 respectively in the 45 said hubs when the blast is on. That is, the hole 10 is adapted normally, as in Fig. 2, to communicate with the blast opening 3, and the hole 12 with the blast opening 4 when the blast is being delivered and a 50 label is being blown upon the bottle. Then when this has been done and another label is moved up by the drum the said hubs are raised momentarily by rod E and the blast is cut off automatically. On the other hand 55 the slots 10' and 12' transverse in the side of cylinder C opposite the recesses h' and h'' in said hubs are constantly open to the suction from beneath. The said recesses h' and h'' respectively in the periphery of hubs 60 H and H' are of a length relatively equal to the length of transverse slots 10' and 12' and the width of two compartments at the cylinder, so as to sustain suction on at least two compartments at a time and in certain 65 positions of the parts on three, and the suc-

tion in any exposed compartment holds until the drum is rotated out of the suction zone into open relation with the blast passages 3 and 4, respectively when said passages are instantly closed, momentarily. 70 This provides for suction for receiving the labels from the label carrying pockets N and N', Fig. 1, and which continues with each pocket as it is carried around past paste pot P and past paste applying roll 15 to the third position opposite the bottle and the blasts. That is to say, by reason of the length of said slots 10' and 12' and recesses h' and h'' and their relations to the several compartment walls 9 successively the 75 suction remains on as to the drums until the third advance movement is reached and the label is brought into attaching position opposite the bottle J. When this position is reached by the label it is ready also to 80 receive the blast which blows it onto the bottle and the compartment or compartments receiving the blast have of course been carried far enough around to cut off the suction, Fig. 3. This, however, leaves the 85 next two approaching compartments still exposed to suction, and label L' is receiving paste from roller 15 while the next succeeding label is about to be received from the 90 label pocket N or N'. It should have been 95 explained that the periphery or outer circle of the drums is provided with scattered perforations d in such number as the nature of the work may require and which extend entirely around both drums. 100 Rotation of the drums is through gear G actuated by gear M on vertical shaft O, and which shaft actuates the bottle carrier mounted thereon. Said carrier has a base 16 fastened upon gear M and constituting 105 a support for the bottles, and a notched or scalloped head disk 17 fixed on the top of the shaft and adapted to engage the necks of the bottles J. The gears G and M are of the same size, and thereby a uniformly 110 timed rotation is obtained for said bottle carrier and the drums D and D'. A second edge scalloped disk 18 is fixed on shaft O next over base 16 and engages the bottoms 115 of the bottles, and said disks 17 and 18 are 120 rotarily adjustable in respect to shaft O so as to bring the bottles exactly opposite the compartments in the drums at the right times for receiving the labels. The said shaft O carries a bevel gear 20 which is in mesh 125 on opposite sides with corresponding gears 21 and 22 on shaft S, and power is conveyed or communicated to both shafts O and S and thence to the parts dependent on said shafts from power shaft T by link 23 to oscillating lever 24 mounted freely on shaft S by the side of ratchet wheel 25, said lever 24 having a spring pressed dog 26 in its end and side adapted to engage the ratchet teeth 27. Lever 24 is connected by 130

said link 23 to crank arm 28 on the power shaft, whereby a constant rotation of said shaft and arm imparts a reciprocating movement to said lever and an intermittent forward movement to ratchet wheel 25. To do this the dog 26 makes engagement with one of said teeth 27 at each complete revolution of crank arm 28 and moves said ratchet wheel forward the distance between teeth 10 and so as to carry cam wheel 8 over one of its cams 7, which exactly correspond with said ratchet teeth. This in turn actuates hubs H and H', as before described, and imparts corresponding rotation to the bottle carrier and thence by gears M and G to the drums, as is now obvious. Gear 21 and ratchet wheel 25 are shown as unitary in this instance, so that rotation of said ratchet wheel also rotates said gear, and 20 then the power divides through gear 20, some of it going by shaft O and some through splined gear 22 and shaft S to cam wheel W. A rubber cushion 29 beneath sleeve 30 on blast tube F relieves the drop 25 of the parts when roller 8 rides off one of the said cams 6.

The labels L in pockets N have followers 31 provided with stems 32, and a bar 33 connecting the ends of said stems is actuated 30 by a feed screw 34 supported on bed B and carrying a pinion 35 in mesh with spaced teeth 36 on the under side of drum D'. A hand grip 37 on screw 34 adapts the same to withdraw the followers by a hand rotation of said screw to replenish the labels, and the said parts are otherwise actuated with each forward movement of the drums. Finally as to the details, it has been found important to have shield plates or guards

40, temporarily interposed between the labels and the suction compartments, said plates being adapted to occupy shielding position normally but also adapted to be retired momentarily as each compartment is moved up 45 before the label pocket to receive a label therefrom. The labels are held back by the shield until the shield is withdrawn and then suction instantly takes up the first label and which closes suction as to the others.

50 The instant this has been done the shield is automatically restored to closing position, as shown in Fig. 3, and so on alternately. To these ends I mount the said shield or plate on an arm 41 which has a loop 42 adapted to receive an actuating lever 43, and the said arm or arms 41 where a dual mechanism is employed, are slidably mounted at their rear ends in holes in a rigid post 44, fixed on base B, while the lever 43 is

60 provided with a longitudinal slot 45 in its lower end and is therein mounted slidably on a supporting bolt 46 or its equivalent fixed in bracket 47 on base B. Two springs, 48 and 49 are connected with said lever, the spring 48 serving to draw said lever down-

ward after an actuation and spring 49, engaged with the lever below its pivot on bolt 46, serving to throw the lever forward at its top and thus restore the shield to shielding position. The reverse or opening movement of the shield is effected through projections 50 on the bottom of gear G corresponding with the compartments in said drums and adapted to strike the extremity of the lever and cause it to swing to open 70 position, relatively as seen in Fig. 6, spring 48 assisting in this action as well as drawing said lever downward after a projection 50 has been passed. The said shield plate is preferably made in one piece for both drums 80 D and D'. The paste roll is rotated by contact with the drum. The so-called hubs H and H' operate in a sense as valves to control both the suction and the blast as to the compartments in the drums D and D', and 85 cut off one or the other in any given position. By reason of the recesses h' and h² being the full depth of the said hubs there is a sustained suction throughout cylinder C in all positions of the hubs and whether 90 suction or blast of air or fluid is communicated with said drums through the hubs.

The suction devices are not shown and need not be as any suitable means for causing exhaust or suction may be coupled up 95 with suction connecting nozzle or pipe a on head A of the cylinder. In this connection it need simply be stated that a continuous or constant suction is maintained through the pipe connection or nozzle a, and it is wholly 100 immaterial what means may be employed for this purpose.

What I claim is:

1. A labeling machine comprising a rotatable drum having an open work periphery and a series of radially divided compartments, suction means to hold the labels on said compartments, a cylinder on which said drum is rotatably mounted having a hole adapted to register with said compartments successively, a reciprocating hub in said cylinder having a duct adapted to register with said hole, and a blast connection engaged with said hub and adapted to blow the labels onto the bottles. 110

2. A labeling machine having a stationary cylinder with a hole in its side and a slideable member in said cylinder having a duct to register with said hole and an air blast delivery pipe open to said duct, in 120 combination with a label carrying drum mounted on said cylinder over said hole and having compartments adapted to communicate with said hole successively.

3. A labeling machine comprising a fixed 125 cylinder having a side hole for air blast, a device in said cylinder adapted to reciprocate and having a duct to register with said hole, and an air blast delivery pipe connected with said device, in combination with 130

a drum on said cylinder constructed to carry labels on its periphery and having compartments adapted to register successively with said opening and walls separating said compartments bearing against said cylinder.

5 4. A labeling machine having a suitable base, a cylinder mounted thereon having suction connections and provided with a blast hole in its side, a device reciprocally 10 mounted in said cylinder having a duct adapted to register with said hole and air blast connection through one end of said cylinder communicating with said duct, in combination with a label carrying drum rotatably mounted on said cylinder over said 15 hole and having compartments adapted to register with said hole successively.

5 5. In a labeling machine, a base and a cylinder resting thereon having exhaust connections and openings in its side, a label carrying drum rotatable upon said cylinder and having compartments adapted to register with said openings, a device reciprocally mounted in said cylinder having a recess across its periphery and a duct separate from said recess communicating with said openings, and suction and blast connections respectively adapted to operate successively in said compartments as said drum 25 is rotated.

30 6. A labeling machine having a cylinder with openings in its side and an exhaust in its lower portion, a drum rotatably mounted on said cylinder having compartments adapted to register with said openings and perforated about its periphery to carry the labels, in combination with a reciprocating air controlling member in said cylinder having a recess in its periphery for 35 the exhaust and a hole to admit the blast, and a blast pipe fixed to said member.

7. In a labeling machine, a suitable base and a cylinder thereon provided with a blast pipe through its top, a drum to carry 40 labels having a perforated periphery and rotatably mounted on said cylinder, a device in said cylinder adapted to be reciprocated and provided with a duct for the passage of the air from said blast pipe, and separate means to rotate said drum and to reciprocate said device successively.

8. In a labeling machine, the combination of a cylinder and separate blast and exhaust connections therein and provided 55 with openings in its side, in combination with drums adapted to carry the labels rotatably mounted upon said cylinder over said openings and provided with successive compartments, a set of fluid controlling 60 members in said cylinder having said blast connections fixed thereto and constructed to pass the exhaust air through the same and separate means to reciprocate said members and to rotate said drums respectively.

65 9. A rotatable label carrying drum and

mechanism to feed the labels thereto, a cylinder on which said drum is mounted having an opening in its side to said drum, a member in said cylinder having a duct for air blast adapted to register with said opening and a recess for air exhaust, in combination with means to reciprocate said member comprising a cam wheel and a shaft actuated thereby and connected with said member.

70 10. The combination of a fixed vertically disposed cylinder having a hole in its side and a rotatable drum about said cylinder having a series of compartments adapted to come opposite said hole successively, in combination with a device in said cylinder having a duct adapted to register with said hole, a rigid tube connected with said device and open to the duct therein, means to operate said device and tube together, and 80 cushioning mechanism engaged with said tube outside said cylinder.

85 11. A label applying machine having a rotatable drum adapted to carry the labels and provided with radially divided compartments and a hollow support therefor, a label holder having substantially the same width as said compartments at the periphery of said drum and suction connections to hold a label on said drum, in combination with an air blast adapted to blow the label off said drum onto the object to receive the same and comprising a reciprocally actuated shut-off located in said hollow support and provided with an air duct.

90 12. A labeling machine for bottles and the like having a fixed hollow cylinder, a drum rotatable thereon provided with an open work periphery, air suction connections to support a label on said drum, separate 105 air blast connections open to said drum and devices adapted to simultaneously cut off the air suction and to turn on the air blast through said cylinder.

100 13. A labeling machine for bottles and the like having a rotatable drum with an open work periphery adapted to carry labels and provided with a series of radially divided compartments corresponding to the labels to be carried, a cylinder upon which 115 said drum is mounted and means therein adapted to open and close said compartments successively to an air blast, air blast connections, suction devices to hold the labels to the drum, and means to rotate said 120 drum.

110 14. A bottle labeling machine comprising a cylinder and a label carrying drum rotatably mounted thereon and provided with a series of radially divided compartments 125 divided at said cylinder, air suction connections to hold the labels on the said drum adapted to be opened to said compartments successively, air blast connections to blow the labels off the said drum onto a bottle, 130

and devices in said cylinder to govern the blast of the air.

15. A bottle labeling machine having a rotatable drum divided into sundry compartments having peripheral walls and a fixed cylinder on which the drum is mounted, said walls extending to the wall of said cylinder, in combination with air suction connections through said cylinder and a movable device in said cylinder having a duct open to an air blast discharging through said cylinder into said compartments successively.
16. A labeling machine for bottles and the like comprising a rotatable drum having radially disposed compartments and an open work periphery, a cylinder on which said drum is mounted provided with an air passage adapted to register with said compartments successively and air blast connections in said cylinder comprising a hub having a duct and a pipe leading thereto, and means to reciprocally operate said hub and pipe.
25. 17. A labeling machine having air suction and air blast connections comprising a stationary cylinder having openings in its side for blast and suction respectively and a reciprocating member in said cylinder adapted to open and close said blast opening successively, in combination with a drum adapted to carry labels rotatably mounted on said cylinder and provided with compartments arranged to turn to said openings successively, said suction connections adapted to sustain the labels on said drum in advance of said blast and comprising a reciprocating hub provided with a recess in its periphery through which suction takes place.
40. 18. In a labeling machine, a pair of drums arranged one above the other and means to rotate the same together, in combination with a fixed hollow bearing upon which said drums are rotatably mounted provided with an exhaust passage at one end and a blast passage at the other end and openings in the wall thereof communicating with said drums, and a device reciprocally mounted in said bearing and provided with ducts adapted to communicate with said openings in the wall of said bearing.

19. A labeling machine comprising a cylinder provided with a pair of openings in its wall and a drum rotatably mounted over each pair of openings and suction devices to hold the labels on the drum, in combination with a hub within said cylinder corresponding to each pair of said openings and ducts therein, means to reciprocate said hubs and means to rotate said drums.

20. In a labeling machine, a suitable base and a cylinder mounted thereon having separate air exhaust and blast connections through its respective ends and provided with openings in its side, and a drum having radial compartments mounted on said cylinder over said openings, in combination with devices reciprocally mounted in said cylinder having ducts to register with said openings, means to reciprocate said devices simultaneously and means to rotate said drum.

21. A labeling machine having a rotatable label carrying drum, a label receptacle, a pasting device for the labels and a rotatable bottle carrier opposite said drum, in combination with suction devices to hold the labels on the drum and an air blast to deliver the labels from the drum to said bottles, said label receptacle having means to temporarily shut off the same from delivery to said drum.

22. A fixed vertically disposed cylinder having a hole and a transverse opening in its side in substantially the same horizontal plane, a drum constructed to carry labels by suction rotatably mounted on said cylinder and having a series of compartments adapted to register with said hole and opening successively, and a device in said cylinder having an air blast duct adapted to register with said hole and a recess in its side to afford a free passage of air exhaust from said drum through the interior of the cylinder by way of said opening.

In testimony whereof I affix my signature in presence of two witnesses.

WILLIAM J. EVANS.
